UNITED STATES PATENT OFFICE.

ROBERT T. JOHNSTON, OF SCOTCH PLAINS, NEW JERSEY, ASSIGNOR, BY MESNE ASSIGNMENTS, TO WOOD & NATHAN COMPANY, OF NEW YORK, N. Y., A CORPORATION OF NEW YORK.

APPARATUS FOR INTAGLIO PRINTING.

1,070,610.

Specification of Letters Patent. Patented Aug. 19, 1913.

Application filed December 21, 1907, Serial No. 407,594. Renewed January 2, 1913. Serial No. 739,900.

To all whom it may concern:

Be it known that I, ROBERT T. JOHNSTON, a citizen of the United States, residing at Scotch Plains, in the county of Union and 5 State of New Jersey; have invented a new and useful Apparatus for Intaglio Printing, of which the following is a specification.

This invention relates to an apparatus for printing from intaglio surfaces.

10 The principal object of the invention is to provide for the employment of engraved intaglio surfaces for printing in a manner somewhat similar to that now used for the best grade of lithography, to print upon 15 ordinary rough paper sheets in such a way as greatly to simplify the apparatus used in lithography, and especially to preserve the sharpness of outline of the intaglio method of printing, thus securing much clearer im- 20 pressions than is possible with any system of lithography. This is secured by mount- 25 ing on a press, preferably of the two-revolution type, an intaglio printing shell, taking impressions from it upon a sheet suitable 30 for receiving the impression and located on an off-set impression cylinder, and trans- 35 ferring an impression directly from that sheet to sheets on the sheet-carrying impression cylinder.

30 As ordinarily practised, the method of printing by lithography in its best form as applied to ordinary rough sheets, involves an initial transfer from an engraved stone to the printing stone or aluminum plate by 35 means of transfer paper, a transfer from said stone or plate to a transfer cylinder, and a final transfer from the latter to the paper. At each of these steps, something 40 of the original sharpness is lost and it is 45 of course well understood, that the original sharpness of a lithographic stone is not to be compared with that of an engraved intaglio plate. By this invention, only two transfers are made and the first of these 50 is always directly from the original intaglio surface, so that the original sharpness is preserved.

55 Reference is to be had to the accompanying sheet of drawings which shows a longitudinal sectional view, somewhat diagrammatic in form, of a press of the two-revolution type arranged for carrying out this invention.

The press is provided with a cylinder or 55 mandrel 10 carrying an engraved intaglio

copper shell 11 which is shown as supplied with ink from an ordinary fountain 12 and ink roller 13 and cleaned by a doctor or cleaning blade 14. Running in contact with the cylinder 10 and at the same circumferential speed, is an off-set impression cylinder 15 provided with two reels 16. This cylinder 15 carries a transfer impression surface, shown as in the form of a rubber blanket 16, held closely in contact with the cylinder 15 by the reels 16—16 with which the blanket is connected and by which it may be adjusted. A sheet-carrying impression cylinder 20 is mounted to run in contact with the rubber blanket and at the same circumferential speed. It is shown as of the form ordinarily employed on a two-revolution press having grippers 21 and the usual eccentric 22 operated by a rod 23 from a lever 24 which is controlled by a cam 25 which is 60 constructed to make one revolution to each two revolutions of the impression cylinder and of the cylinders 10 and 15. By this means, obviously, the impression cylinder 20 is brought into contact with the blanket of 65 the off-set cylinder on alternate revolutions. The usual feed-board 30 and shoo-flies 31 or the like are indicated in the drawings. Gears 35, 36, 37 and 38 are indicated for 70 giving the desired rotary motion to the three 75 cylinders.

70 It will be seen from this description, that a positive design may be engraved in the first instance on the copper plate 11 which is put in the press, and the design transferred to the transfer surface or rubber sheet as a negative, from which it is again printed directly upon the paper. Therefore, only 80 two transfers occur and each impression is transferred from an intaglio printing plate 85 with all its sharpness instead of from a lithographic stone or aluminum plate, the design of which is constantly widening and growing more ragged and which in its original form, is not as sharp in design as the 90 engraved plate. This makes the device suitable for printing commercial work upon 95 rough paper and capable not only of doing the work more economically, but of producing results much better than those now produced by the best method of lithography 100 which has been described above.

105 While I have illustrated and described a preferred embodiment of the invention, I am aware that many modifications may be made 110

therein by any person skilled in the art and that the invention may be carried out with numerous changes in the mechanism employed, within the scope of the claims.

Having thus described my invention, what I claim is:—

1. In a two-revolution sheet printing press, the combination of a cylinder, a shell thereon, having a positive design engraved 10 on its surface, means for inking and cleaning said shell, an offset cylinder located on the side of the first named cylinder opposite the inking and cleaning means, a transfer sheet held on said cylinder and adapted to receive a negative impression from said shell, an impression cylinder for carrying sheets into contact with the transfer sheet, to receive a positive impression, means for rotating said cylinders at the same circumferential rate of speed, means for operating 15 the transfer cylinder, and means operated by the last named means for moving the impression cylinder toward and from the transfer cylinder on alternate revolutions.
- 20 2. In a two-revolution sheet printing press, the combination of a cylinder, a cop-

per shell thereon, having a positive design engraved on its surface, means for inking and cleaning said shell, an offset cylinder having a pair of reels thereon and located 30 on the side of the first named cylinder opposite the inking and cleaning means, a transfer sheet held on said cylinder by said reels, adjustable by the reels, and adapted to receive a negative impression from said shell, an impression cylinder for carrying sheets into contact with the transfer sheet, to receive a positive impression, means for rotating said cylinders at the same circumferential rate of speed, means for operating 35 the transfer cylinder, and means operated by the means for operating the transfer cylinder for moving the impression cylinder toward and from the transfer cylinder on alternate revolutions. 40

In testimony whereof I have hereunto set my hand, in the presence of two subscribing witnesses.

ROBERT T. JOHNSTON.
